UNITED STATES PATENT OFFICE.

GUSTAV L. JAEGER, OF NEW YORK, N. Y.

LEAD OR CRAYON HOLDER.

SPECIFICATION forming part of Letters Patent No. 273,093, dated February 27, 1883.

Application filed November 18, 1882. (No model.)

To all whom it may concern:

Be it known that I, GUSTAV L. JAEGER, a citizen of the United States, residing at New York, in the county and State of New York, have invented new and useful Improvements 5 in Lead or Crayon Holders, of which the following is a specification.

This invention relates to the means for supporting or retaining in position in the lead-receptacle of the handle the movable lead or crayon; and it consists in a lead-clamping shackle which intersects the plane of the lead-receptacle, and a finger-spring on the side of the handle, which has one end attached to the latter and the other end connected to the shackle, and which acts on the shackle with a tendency to draw the same toward it, so that, if the lead is caused to pass through the eye of the shackle and the latter is permitted to follow the action 10 of its spring, the edge of said eye binds or impinges against the lead or crayon, thus preventing its endwise movement, whereas by simply depressing the spring the shackle may be displaced to release the lead.

It consists, also, in the arrangement of the lead-clamping shackle in a recess in the side of the handle, such recess intersecting the lead-receptacle and being above the lower end or tip of the handle, and the finger-spring being 20 attached to the handle at a point above the recess, so that a solid bearing is afforded below the shackle to the fingers of the writer as well as to the lead contained in the receptacle.

This invention is illustrated in the accompanying drawings, in which Figure 1 represents a part section and part side view. Fig. 2 is a cross-section on the line $x-x$, Fig. 1. Fig. 3 illustrates a modification, partly in side view and partly in section. Fig. 4 is a cross-section on the line $y-y$, Fig. 3.

Similar letters indicate corresponding parts.

The letter A designates the handle or sheath, having a bore or tube in the center thereof, forming the lead-receptacle o. C denotes the shackle for clamping the lead, and D the finger-spring on the side of the handle acting on the shackle. Said shackle and spring are integral, they being formed of a single piece of sheet metal, wire, or the like, properly bent, 45 and one end of the spring being thus connected to the shackle, its other or opposite end is attached to the handle A. The eye or hole s

of the shackle is similar in shape and diameter to the lead-receptacle o, so that the eye is adapted to coincide therewith. In the example shown in Figs. 1 and 2 the handle is provided with a recess, i, a short distance above its lower end or tip, of sufficient depth to intersect the lead-receptacle o, and the shackle C is arranged in said recess, while the point at 55 which the spring D is fastened to the handle is above the recess, and in the example shown in Figs. 3 and 4 the shackle is situated below the lower end of the handle, it being in either case in a position to intersect the plane of the lead-receptacle. In the example last named the shackle and its spring, moreover, are doubled, the two members being opposite to each other. The action of the spring D is to draw the shackle toward it—namely, in a direction transverse to the lead-receptacle o—and if the lead introduced into this receptacle is caused to pass through the eyes s of the shackle, it is firmly held in the desired position by the contact therewith of the edge of said eye, while 65 when it is desired to release the lead it is only necessary to depress the spring, thereby displacing the shackle. By arranging the shackle C and its spring in the manner shown in Figs. 1 and 2 a solid bearing is afforded below the 70 shackle, not only to the fingers of the writer, but also to the lead contained in the receptacle, so that the pencil is convenient in use and the lead is least liable to break.

It will be seen that the devices herein described are simple in construction, thus allowing the pencil to be manufactured at a low cost, are easily operated, and are not liable to get out of order.

If desired, the pencil-lead can be provided 85 with notches for engagement with the shackle.

I am aware that a brace for bits has had its bit-receiving socket provided with a transverse slide slotted for the passage of the bit-shank, one edge of the slot being adapted to engage 95 a notch in the bit-shank by the action of a coiled spring, the slide having a finger-piece, by pressing on which the slide is disengaged from the bit-shank. Such, however, is not my invention, and is not claimed by me.

What I claim as new, and desire to secure by Letters Patent, is—

1. The combination, substantially as hereinbefore set forth, with the handle having the

central lead-receptacle, of the lead-clamping shackle, arranged to intersect the plane of said receptacle, and the finger-spring on the side of the handle, having one end attached to the latter and the other end connected to the shackle and acting on the shackle with a tendency to draw the same toward it, for the purpose specified.

2. The combination, substantially as hereinbefore set forth, with the handle having the central lead-receptacle and having the recess intersecting said receptacle above the lower end or tip, of the lead-clamping shackle, ar-

ranged in said recess, and the finger-spring on the side of the handle, having one end attached to the latter at a point above the recess and the other end connected to the shackle and acting on the shackle with a tendency to draw the same toward it, for the purpose specified.

In testimony whereof I have hereunto set my hand and seal in the presence of two subscribing witnesses.

GUSTAV L. JAEGER. [L. S.]
